PROTECTIVELY COVERED ARTIFICIAL LEG
AND SKIN-LIKE COVERING THEREFORSteven L. Hansen and Orlan K. Hedrick,
Salt Lake City, Utah

Application August 20, 1951, Serial No. 242,672

6 Claims. (Cl. 3—2)

1

This invention relates to the art of prosthesis, particularly in connection with artificial legs.

Artificial legs as ordinarily constructed are devoid of superficial covering. The ankle joint and the knee joint, if the latter be present, are customarily left open and unprotected, except for the usual hosiery worn with the leg. As a result, the hosiery is subjected to seriously destructive chafing at the joint or joints, and dust and dirt tend to filter into the latter. The most that has been heretofore proposed to take care of these difficulties is an elastic band broad enough to comprehend a joint, and anchored to the leg above and below the joint. This has never proven satisfactory in practice.

In accordance with the present invention, we provide an elastic, skin-like covering over substantially the entire artificial leg, such covering being in the form of a snugly fitting stocking otherwise unattached to the leg. This gives sufficient freedom of action at the joints to largely overcome any tendency toward constantly repeatedly localized stretch and return of the covering material during use of the leg.

A feature of preferred embodiments of our invention resides in making portions of the skin covering at the joints thicker and therefore less resilient than other portions, to still further overcome the tendency toward concentration or localization of the effect of activity of the joint by directing the stretching action into the body of the covering in general.

In the most preferred form of the invention, the thickened and less resilient portion of the ankle joint is a broad band provided with a depending appendage in the nature of a saddle covering the sole of the foot for anchoring the ankle band against response to joint movement.

We have found that this unattached skin-like covering tones up the action of the limb, because of its extensive and comprehensive elasticity.

Important subsidiary features of our invention reside in the tapering of the upper margin of the covering inwardly to lesser diameter than called for by the particular leg concerned, for effecting resilient anchorage to the leg, and in the provision of a rough exterior surface for the covering, serving to frictionally anchor the customary dress hosiery in place when applied over the protectively covered leg. In this connection, we prefer to make the interior surface of the covering smooth and substantially non-adherent, to facilitate initial positioning upon the leg and to enhance the aforementioned dissipation of essen-

2

tially local activity into the body of the covering generally.

We have found that users of our improved artificial legs experience considerably greater satisfaction than has been possible heretofore. Not only are previous difficulties overcome, as mentioned above, and the wearing of usual types of hosiery facilitated, along with improved limb action, but the entire leg is given a more natural appearance when the covering is made in skin colors.

Since the skin covering may be fabricated and sold independently of an artificial leg, for subsequent application to the leg by a user, our invention is directed to the artificial skin covering per se, as an article of manufacture, as well as to the combination.

Additional objects and features of the invention will become apparent from the following detailed description of the particular preferred embodiments illustrated in the accompanying drawing.

In the drawing:

Fig. 1 represents a side elevation of an artificial leg equipped with an artificial skin covering in accordance with the invention;

Fig. 2, a similar view showing the skin covering in vertical section;

Fig. 3, a perspective view of the skin-like covering per se prior to the application of the artificial leg; and

Fig. 4, a view corresponding to that of Fig. 2, but showing the skin-like covering comprehending the knee joint.

Referring to the drawing: the artificial leg proper of Figs. 1 and 2, is indicated 10, and may be of any usual construction. It possesses an ankle joint 11, which articulates during use of the limb, and ordinarily is the cause of rapid wear and deterioration of dress hosiery customarily worn over the leg. Furthermore, articulation of the joint ordinarily facilitates entry of dust and dirt to the working parts, resulting in rapid wear thereof.

In accordance with our invention, the artificial leg 10 is completely encased by a protective, artificial skin-like covering 12, having the general formation of a stocking, and being applied without actual fastening to the limb.

The artificial skin-like covering 12 is usually formed independently of the artificial leg, from rubber latex or similar material, and is applied to the leg thereafter in the manner of a stocking. As applied, it hugs the leg, but permits freedom of action of the joint, substantially

without localized stretch at and surrounding the joint.

The most practical way of making the covering 12 is by repeatedly brushing or spraying rubber latex solution on a suitable form having the shape of the particular artificial leg concerned, or by repeatedly dipping the form into a body of rubber latex solution.

Prior to the application of the rubber latex solution, a band 13 of rubber or similar substance having a thickness greater than the thickness of the latex skin, is applied to the form at and around the location of the ankle joint. In the embodiment illustrated, such band 13 advantageously has a dependent appendage 13a designed as a saddle to cover the sole of the foot portion of the particular leg concerned, thereby anchoring the ankle band 13 against activity of the ankle joint 11. It should be noted that both the band 13 and saddle appendage 13a serve, additionally, as cushions for ankle and foot activity.

As so applied to the form prior to the application of the rubber latex solution, such ankle band 13 and anchoring appendage 13a are covered and thoroughly tied into the resulting article by the coagulated latex, which tends to fill out and round the surface irregularities. A smooth interior surface is thereby provided for the resulting article, and at least an approximation to an even contour for the outside surface. Where considered necessary or advisable, additional latex solution may be applied by brushing or spraying particular localized areas, even though a dipping procedure has been followed in general.

For the purpose of providing the desired rough exterior surface, indicated at 14 in Figs. 1 and 3, it is preferred that the final coat of latex solution be roughened by brushing in those instances where the previous coats were applied by spraying or dipping, though, of course, other roughening procedures may be employed, as, for example, the roughness may be actually molded in, regularly or irregularly by the application of suitable mold forms to the surface while yet plastic.

The form to which the latex solution is applied advantageously has its upper end tapered inwardly, so as to produce in the article as such, an inwardly tapered upper margin, as at 15, Fig. 3, having a diameter effectively less than the diameter, in that vicinity, of the particular artificial leg concerned. This constricted upper margin, then, serves to positively anchor the covering in position on the artificial leg.

Instead of utilizing a preformed band 13 and appendage 13a, the same may be provided by first brushing or otherwise applying rubber latex solution to only those particular localized areas of the form concerned, the application being repeated until a proper thickness for the parts is built up directly on the form.

Regardless of how provided, however, the wall thickness for these critical parts of the skin covering is sufficiently greater than the wall thickness of the remainder of the covering to effect the primary purpose thereof, as set forth hereinbefore, as well as to withstand any chafing action of the joint. Normally, the thickness of these parts will be more than twice the thickness of the remainder of the covering. Generally speaking, it is advantageous, both from the stand-

ing of function and appearance, to keep the wall thickness of major areas of the covering substantially uniform.

In those instances where the artificial leg comprehends both ankle and knee joints, as in Fig. 4, where the knee joint is indicated 16, an additional band 17 is provided at and around such knee joint, such band being incorporated in the skin covering as a whole in the same manner as the ankle band 13.

Whereas this invention is here illustrated and described with respect to certain preferred specific forms thereof, it should be understood that various changes may be made without departing from the scope of the following claims.

We claim:

1. An artificial leg, comprising a leg proper having at least one articulative joint, and an elastic, skin-like covering in the form of a stocking molded to shape from a rubber material, said covering closely hugging the leg proper without attachment thereto, and portions of said rubber material at and in the vicinity of said joint being effectively thicker than the remainder to direct localized activity of the joint into the body of the covering.

2. An artificial leg, comprising a leg proper

having an articulative ankle joint; and an elastic skin-like covering in the form of a stocking molded to shape from a rubber material, said covering closely hugging the leg proper without attachment thereto, and including a broad band portion of rubber material at and surrounding said ankle joint as well as a saddle appendage

35 depending from said band and passing through the sole of the covering, said band and its saddle appendage having a thickness greater than the remainder of the covering to direct localized activity of said ankle joint into the body of the covering.

3. The combination recited in claim 2, wherein the skin-like covering has its top margin stretched tightly about the leg proper, as an elastic anchor.

45 4. The combination recited in claim 2, wherein the exterior surface of the skin-like covering is rough textured.

5. A skin-like covering for artificial legs, comprising an elastic stocking molded to shape from a rubber material and having a configuration substantially matching that of the artificial leg to which it is to be applied, said covering having portions at and in the vicinity of a joint effectively thicker than the remainder.

55 6. A skin-like covering for artificial legs, comprising an elastic stocking molded to shape from a rubber material and having a configuration substantially matching that of the artificial leg to which it is to be applied, the sole of said stocking having a thickness exceeding the general wall thickness of said stocking, to provide for cushioning action.
